FOLDING DOOR

Anthony Madonna, Detroit, Mich.

Application July 19, 1946, Serial No. 684,652

8 Claims. (Cl. 160—213)

1

The present invention pertains to a novel folding door for a receptacle and particularly for the inner perforated rotary drum of a washing machine.

The principal object of the invention is to provide a door for this purpose that is simply and inexpensively constructed and which folds to its open position. Preferably, a positive means is provided for retaining the door in either opened or closed position.

In the accomplishment of this object, the door consists of two sections hinged to one another, one of the sections being hinged to an edge of the door opening. Thus, the door folds inwardly of the receptacle when in the open position. In the case of a cylindrical drum for a washing machine, the door sections are curved on the radius of the cylinder so that they lie in the cylindrical surface of the drum when the door is closed.

A spring latch is carried by one of the sections and locked against a rail fixedly mounted in the receptacle and slightly inward of the opening. The rail is formed with a slope or bevel where engaged by the latching member in the locking position, and the slope or bevel is so positioned as to retain the latching member in the locking position. The rail also has an inwardly extending portion on which the free edge of the door rests when in the open position. Further, this portion of the rail is preferably formed with a seat to receive the rolled or beaded free edge of the open door, thereby retaining the latter positively in the open position.

The invention is fully disclosed by way of example in the following description and in the accompanying drawings in which:

Figure 1 is a side elevation of a washer constructed according to the invention, the outer drum being broken away for illustration;

Figure 2 is a section on the line 2—2 of Figure 1;

Figure 3 is an enlarged detail thereof;

Figure 4 is an enlarged detail of Figure 1, and

Figure 5 is a section on the line 5—5 of Figure 3.

Reference to these views will now be made by use of like characters which are employed to designate corresponding parts throughout.

The washer is of the horizontal cylinder type and includes an outer closed drum 1 mounted on a shaft 2 which in turn is journalled in upright bearings 3. On the shaft 2 is rotatably mounted an inner wash drum including a suitable number of circular rims 4 supported on the shaft and in turn supporting the perforated cylindrical drum sections 5. The sections 5 are pref-

erably dented inwardly and longitudinally to form ribs or vanes 6. Each section 5 has a loading opening 7, and adjacent to each such opening the outer drum 1 is formed with a similar opening 7'. The latter are disposed above the horizontal diametrical plane and need not be covered since the inner drum is merely oscillated by suitable well known mechanism provided for that purpose.

10 The door for each opening 7 comprises a pair of plates 9 and 10 bent arcuately on the radius of a cylindrical section 5. The plate 9 is hinged at 11 to the section 5 at the upper edge of its opening 7. The plate 10 is attached to the remaining edge of the plate 9 by a series of leaf hinges 12, as shown more clearly in Figure 4. The free edge of the plate 10 is beaded at 13 for finish, as shown more clearly in Figure 3. The plates 9 and 10 are also perforated at 14 as shown in Figure 3.

15 An arcuate rail 15 is provided at each end of each opening 7 and is supported by the end plates 16 of the sections 5 or by internal partitions. The rails are substantially co-extensive with the corresponding openings 7 and are spaced somewhat inward of the cylindrical surfaces of the sections 5 extended over the openings 7. The beads 13 contain rods 17 adapted to ride upon the rails. The upper ends of the rails are directed inwardly 20 of the sections 5 as indicated by the numeral 18 in Figure 3.

25 When a pair of arcuate plates 9, 10 is alined in the cylindrical surface of the section 5, they close the opening 7 as may be seen in Figures 2 and 3. The door is opened by pushing the edge 13 up onto the extended portions 18 of the rails thereby throwing the sections 9, 10 inwardly as shown in the same figures. Again, on closing the door, the section 9 swings on the hinge 11 and the section 10 on the hinges 12, both sections passing between the rails to occupy the closed position shown in full lines.

30 Each door section 9 carries a stamped metal housing 19 near each edge and close to the axis of the hinge 12. The housings are disposed on the inner surface of the section 9 when the door is closed, and each contains a tubular guide 20 in which is slidably mounted a latch pin 21. The latter is pressed into engagement with the side of the adjacent rail 15 by a coil spring 22 behind it and within the tube 20.

35 As the door comes to a closed position, the pin 21 rides down a slope 23 formed on the side of the adjacent rail 15, as shown in Figure 5. The engaging end of the pin 21 is correspondingly

bevelled at 24. The door will not slip open inasmuch as the spring-pressed pin 21 will not ride upward of the slope 23 unless forcibly pulled back. Also, the bead 13 wedges against an angle iron 18' laid across two opposed vanes 6. In order to permit retraction of the latch pin to open the door, the pin is provided with a laterally extending finger 26 accommodated in a slot 27 formed in the tube 20, and accessible through an opening 19' in the housing 19.

In the use of the device, it is now apparent that the door is closed from the dotted line position shown in Figures 2 and 3 by being pulled into the opening 1 and passing between the rails 15. The latch pins 21 engage the sides of the rails and lock behind the slopes 23 in the manner described. To open the door, the latch pins 21 are pulled inward by the fingers 26, and the door is then folded back to the dotted line position.

In the open position of the door the rods 17 rest on the inwardly extending portions 18 of the rails 13 and are seated in notches or grooves 28 formed in the portions 18. In this position the rib 6 next adjacent to the open door overlies the joined edges of the door sections, as shown in Figure 2, since the distance from the hinge 11 to the rib is substantially equal to the distance between the hinges 11 and 12. The rib 6 thus protects the inner edge of the open door from catching articles that might be thrown around inside the drum, which articles would tend to close the door by their weight.

Although a specific embodiment of the invention has been illustrated and described, it will be understood that various alterations in the details of construction may be made without departing from the scope of the invention as indicated by the appended claims.

What I claim is:

1. In a cylindrical drum having an opening in its cylindrical wall, a door for said opening comprising two sections hinged together on a line parallel to the axis of said drum, one of said sections being also hinged to said drum at an edge of said opening, a rail secured to said drum slightly inward of said opening and positioned to guide one of said sections, and a latch carried by one of said sections and adapted to lock on said rail, said rail having an inwardly extending portion near said edge of said opening, the free edge of the remaining section being adapted to rest on said portion when the door is open.

2. In a cylindrical drum having an opening in its cylindrical wall, a door for said opening comprising two sections hinged together on a line parallel to the axis of said drum, one of said sections being also hinged to said drum at an edge of said opening, a rail secured to said drum slightly inward of said opening, and a spring-pressed pin carried by one of said sections, a side of said rail being bevelled and engageable by said pin to lock the same.

3. In a cylindrical drum having an opening in its cylindrical wall, a door for said opening comprising two sections hinged together on a line parallel to the axis of said drum, one of said sections being also hinged to said drum at an edge of said opening, a rail secured to said drum slightly inward of said opening, and a spring-pressed pin carried by one of said sections and adapted to lock on said rail, said rail having an inwardly extending portion near said edge of said opening, the free edge of the remaining section being adapted to rest on said portion when the door is open.

4. In a cylindrical drum having an opening in its cylindrical wall, a door for said opening comprising two sections hinged together on a line parallel to the axis of said drum, one of said sections being also hinged to said drum at an edge of said opening, a rail secured to said drum slightly inward of said opening, a latch housing carried by one of said sections, a latch pin slidably mounted in said housing towards said rail, and spring means urging said pin towards said rail, a side of said rail being bevelled and engageable by said pin to lock the same.

5. In a receptacle having an opening in its wall, a door for said opening comprising two sections hinged together, one of said sections being also hinged to said receptacle at an edge of said opening, a rail secured to said receptacle slightly inward of said opening, and a latch carried by one of said sections and adapted to lock on said rail, said rail having an inwardly extending portion near said edge of said opening, the free edge of the remaining section being adapted to rest on said portion when the door is open.

6. In a cylindrical drum having an opening in its cylindrical wall, a door for said opening comprising an upper section and a lower section hinged together on a line parallel to the axis of said drum, the upper section being also hinged at its upper edge to said drum at the upper edge of said opening, the upper section being swingable into the drum and the lower section being swingable onto the outer surface of the upper section to dispose said sections inside the drum on opening the door, a pair of rails secured to said drum slightly radially inward of said opening, said rails being spaced apart a greater distance than the width of said doors axially of said drum, whereby said sections may pass between said rails, members on said lower section and riding on said rails, and means at the upper ends of said rails for retaining said members.

7. In a cylindrical drum having an opening in its cylindrical wall, a door for said opening comprising an upper section and a lower section hinged together on a line parallel to the axis of said drum, the upper section being also hinged at its upper edge to said drum at the upper edge of said opening, the upper section being swingable into the drum and the lower section being swingable onto the outer surface of the upper section to dispose said sections inside the drum on opening the door, a pair of rails secured to said drum slightly radially inward of said opening, said rails being spaced apart a greater distance than the width of said doors axially of said drum, whereby said sections may pass between said rails, members on said lower section and riding on said rails, and means at the upper ends of said rails for retaining said members, said means lying in close proximity to the hinged upper edge of the upper section, whereby the open sections substantially clear said opening.

8. In a cylindrical drum having an opening in its cylindrical wall, a door for said opening comprising an upper section and a lower section hinged together on a line parallel to the axis of said drum, the upper section being also hinged at its upper edge to said drum at the upper edge of said opening, the upper section being swingable into the drum and the lower section being swingable onto the outer surface of the upper section to dispose said sections inside the drum on opening the door, a pair of rails secured to said drum slightly radially inward of said opening, said rails being spaced apart a greater distance than the

width of said doors axially of said drum, whereby said sections may pass between said rails, members on said lower section and riding on said rails, each rail having an inwardly extending portion at its upper end, and means on said portions for retaining said members.
